UNITED STATES PATENT OFFICE.

JOHN F. MORLEY, OF LANSING, MICHIGAN.

IMPROVEMENT IN SAFETY TRACE-FASTENERS.

Specification forming part of Letters Patent No. 117,195, dated July 18, 1871.

To all whom it may concern:

Be it known that I, JOHN F. MORLEY, of Lansing, in the county of Ingham and State of Michigan, have invented a new and valuable Improvement in Safety Trace-Fastener for Whiffle-trees; and I do hereby declare that the following is a full, clear, and exact description of the construction and operation of the same, reference being had to the annexed drawing making a part of this specification, and to the letters and figures of reference marked thereon.

Figure 1 of the drawing is a perspective sectional view of the invention with the trace fastened. Fig. 2 represents the device unfastened, attached to either end of the whiffle-tree, A being closed, and B being opened or a sectional view. Fig. 3 represents the device locked and attached to either end of a whiffle-tree, A being closed, and B being opened or a sectional view.

K represents the trace or tug of a harness fastened to the whiffle-tree by the invention. S S represents the sockets by which the invention is attached to the whiffle-tree. T T represent the whiffle-tree. F F represent a fly-plate with an aperture in the front end to admit the catch C, and also an aperture in back end through which to fasten the strap H, and back of which is a steel spring, E, which holds the fly in place on bolt C when fastened. C C is the catch which passes through the cock-eye of the trace, and thence through the fly-plate F when the trace is fastened back to the whiffle-tree. M M is an attach-

ment to or a part of catch C, which passes over steel spring D, which causes the bolt to fly out when it is released from fly-plate F by pulling the strap H. H is a strap attached to fly-plate F, and passes up to the dash-board of the carriage to which the whiffle-tree is attached, and by pulling which the steel spring E is pressed back by the front end of the fly-plate F, which works or flies on pivot P, and which also passes back until it releases the catch C, when the bolt G, which works on pivot X, is thrown out by action of the spring D and the trace is released from the whiffle-tree.

In case of breaking the traces or one of the traces of the harness, the action of the whiffle-tree will cause the other trace to press against the fly-plate F sufficiently to release the catch C, and also thereby the trace which remained fastened at the time of the accident, and allow a frightened animal to be released from the carriage without further accident or damage.

The invention is to be made of metal.

I claim as my invention and on which I desire Letters Patent—

The fly-plate F with the apertures for admitting the catch C and strap H, also the catch C with its attachment M, in combination with the steel springs D and E and the strap H, substantially as and for the purposes specified.

Witnesses: JOHN F. MORLEY.
